IGNITION APPARATUS

Giltner J. Knudson, Guilford, N.Y., assignor to Bendix Aviation Corporation, Sidney, N.Y., a corporation of Delaware

Application September 11, 1956, Serial No. 609,283

6 Claims. (Cl. 310—156)

This invention relates to electrical apparatus and more particularly to apparatus for generating current such as that required for the ignition system of internal combustion engines.

One of the objects of the present invention is to provide a novel current generating apparatus of increased efficiency.

Another object of the invention is to provide current generating apparatus, such as a magneto, wherein the pole members of the stator are of novel configuration and allow the marked conservation of overall size of the apparatus.

Still another object of the invention is to provide current generating apparatus, such as a magneto, wherein the pole members of the stator are of such configuration and interact with the pole pieces of the rotor in such manner as to yield appreciable greater current generating efficiency.

A further object is to provide a magneto of decreased girth while allowing ready accessibility to the current generating coil thereof.

Still another object is to provide a magneto having a stator provided with pole members of such configuration that the coil lies beyond an end of the rotor and at least partially overlies such end of the rotor.

A still further object is to provide a magneto for supplying the ignition needs of a multi-cylinder engine wherein each pole member on one of the relatively movable parts of the magneto interacts simultaneously with a plurality of pole pieces of like polarity on the other part of the magneto, whereby the magneto has an increased magnetic efficiency.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention.

In the drawings, where like characters refer to like parts throughout the several views,

Fig. 1 is a view in longitudinal section through one form of magneto embodying the invention, the section being taken generally along the axis of the magneto shaft, certain parts including the magneto shaft and a portion of the distributor cap on the magneto being shown in elevation.

Fig. 2 is a rear end elevation of a magneto taken along the line 2—2 of Fig. 1, the rear shaft-supporting end member and the breaker point assembly having been removed.

Fig. 3 is a view in perspective of an assembly of pole members before its incorporation as an insert in the housing of the magneto.

Fig. 4 is a view in transverse section through the magneto, the section being taken generally along the line 4—4 of Fig. 1, the pole pieces of the rotor being shown

2

in neutral position with respect to the pole shoes of the stator.

Fig. 5 is a view in perspective of the rotor of the magneto, the view being taken in a direction from the rear to the front end thereof.

Fig. 6 is a view in rear end elevation of the rotor of the magneto.

Fig. 7 is a view in rear end elevation of the pole member assembly of the magneto, portions of the assembly being partially broken away at the location of the pole shoes of the pole members.

Fig. 8 is a view in rear end elevation of the rotor and pole member assembly of the stator in operative relationship, the pole pieces of the rotor being shown in registry with the pole shoes of the stator.

The embodiment of the invention illustrated in the drawings, by way of example, is in the form of a magneto for an eight-cylinder internal combustion engine wherein combustible charges are ignited by timed electrical discharges across the spark gaps in the respective cylinders. In Fig. 1 the magneto is shown as having a housing 10 carrying a shaft 11 in a front bearing 12 and a rear bearing 13 supported in such housing. Affixed to shaft 11 is a rotor 14 having eight equally angularly spaced outer pole pieces thereon.

The pole pieces of the rotor interact with the stator having opposed pole members 37 and 37' (Fig. 3) carried by the housing 10, in a manner to be explained, thereby producing cyclically varying flux in the pole members. Legs 15, leading from the pole shoes of the pole members, and lying offset from the axis of the rotor as shown in Fig. 1, are bridged by the core 16 of a current generating coil 17 having a primary and a secondary winding.

The rear or outer end of housing 10 is provided with a seat 18, best shown in Fig. 2, which receives the inner or rear end member 19 supporting bearing 13. Cap 19 carries an inwardly directed flat spring of generally U-shape, the opposed legs 20 (one shown in Fig. 1) lie outwardly of the ends of coil 17 and press core 16 of coil 17 firmly into engagement with the outer ends of legs 15. Preferably, the flat spring is made of non-magnetic metal such as a copper-beryllium alloy.

The magneto includes a conventional breaker point assembly 21, which opens and closes the primary circuit of the coil at pre-determined times in the cycles of flux variation in the magneto, and a condenser 22 connected across the breaker points. The outer end of shaft 11 carries a distributor rotor 23 which cooperates successively with fixed contacts (not shown) on the inner face of distributor cap 24, the rotor successively connecting the spark gaps of the engine cylinders to a high tension lead wire (not shown) connected to terminal 32 of coil 17. The cap is provided with eight terminal housings 25 for receiving wires leading to the spark gaps of the respective cylinders.

The rotor 14 of the magneto has an annular magnet 26 affixed thereto, a first generally cup-shaped four-armed member 27 being positioned on the rotor shaft at one end of the magnet and a second, similar four-armed member 28 being positioned on the shaft at the other end of the magnet. Members 27 and 28 are non-rotatably affixed to shaft 11 so that the arms 30 of member 27 and the arms 29 of member 28, which overlie the outer surface of magnet 26, are parallel to and equally angularly spaced from each other. The opposite ends of magnet 26 have opposite magnetic polarities so that the arms 29 constitute, for example, magnetic pole pieces having a north polarity and arms 30 constitute pole pieces having a south polarity. It will be evident that adjacent pole pieces of the rotor have their centers displaced throughout an angle AOB (Fig. 6) of 45° from

each other in the same central transverse plane through the rotor.

In the embodiment of the magneto shown the opposed pole members of the stator each includes two pole shoes displaced 90° from each other about the axis of the stator and so positioned as to coat simultaneously with two pole pieces on the rotor having the same magnetic polarity, the pole shoes of the opposed pole members coacting with pole pieces of opposite polarity.

The construction of the opposed pole members, and of the assembly thereof prior to their incorporation as a unit in the housing 10 of the magneto, will best be understood by consideration of Fig. 3. The pole member assembly, designated generally 36, is in this embodiment made up of two opposed pole members which are mirror images of each other and which in unit 36 are held together by end plates 39, 40, and 41 made of non-magnetic metal. Accordingly, for simplicity, the same reference characters but with added primes are employed to designate parts of the left hand pole member 37' (Fig. 3), as those used in connection with the right hand pole member 37. Detailed description of the pole members will be primarily confined to pole member 37.

The pole shoes and their extensions are made of laminations of magnetic metal such as iron or steel.

Pole member 37 has an upper pole shoe 34, the center of which lies in an axial plane displaced 22½° above the horizontal (Fig. 7). Pole member 37 has a second, lower pole shoe 35, the center of which lies in an axial plane displaced 22½° from the vertical and on the same side of a vertical axial plane as pole shoe 34. Consequently, pole shoes 34 and 35 are displaced 90° from each other, and are thus in position to confront alternate rotor pole pieces of the same magnetic polarity. Lower pole shoes 35 and 35' are displaced 45° from each other. The pole shoes 34 and 35 when connected parallel in the magnetic circuit produce a much greater flux density in such circuit than yielded by either of such pole shoes alone. Pole shoes 34 and 35 are connected by extensions of the pole shoes, such extensions including a leg 42 and a leg 46, respectively, which extend outwardly or rearwardly parallel to the axis of the rotor and close to each other to form a combined leg 15. In the form shown, the outer ends of legs 42 and 46 are riveted together. The upper leg 42 has its inner face 43 or tapering beveled in a forward direction, so that the inner end of the leg is of reduced width. Such inner end of the leg is connected with a sweeping right angle band to a circumferential extending extension part 44. The radially inner face of extension part 44 is spaced appreciably outwardly from the rotor, the shoe 34 constituting a radially inwardly projecting part on member 44. To improve the magnetic efficiency of the device, pole member 37 is provided with side filler laminations or plates 45 at both sides thereof throughout the zone of the pole shoe 34 and extension part 44, thereby increasing the effective cross section area of the pole member in such zone.

The bottom pole shoe 35 is, as we have seen, connected in parallel with pole shoe 34 by an extension including leg 46. Leg 46 extends forwardly from the free end of combined leg 15 generally parallel to leg 42 to a location generally below member 44. At such position the extension is bent sweepingly downwardly into a first leg 47 of a U-shaped portion of the extension. Such U-shape portion lies generally in the central transverse plane containing pole shoes 34 and 35. The other leg 49 of such U-shaped portion lies generally parallel to leg 47 and rises to terminate at its top in the generally radially directed lower pole shoe 35. Side filler plates 50 are provided at the lower pole shoe, such filler plates also overlying the leg 49 of the extension.

The two opposed pole members 37 and 37' are retained in the desired relationship by end retainer plates which are made, for example, of brass. A rear upper

retainer plate 40 having a general central rotor-receiving aperture therethrough is connected to the pole members by rivets extending through ears on plate 40 and through the extensions of the upper pole shoes. A lower rear plate 39 is connected to legs 49 and 49' of the lower pole shoes by rivets as shown. A unitary forward retaining plate 41 made, in effect, to combine the shapes of the rear plates 39 and 40, is connected to the assembly by the same rivets, which connect plates 39 and 40 to the pole members.

As will be clear in Fig. 4, the pole member assembly 36 is imbedded in the housing 10 of the magneto. In the embodiment shown, the housing 10 is an integral casting made of a non-magnetic metal, such as aluminum, having a melting point appreciably lower than the melting point of the pole members and their retaining plates. The pole member assembly 36 is disposed as an insert in a suitably shaped mold, and the metal to form housing 10 is then cast about such insert. The pole member assembly and the opposed pole members 37 and 37' thereof, forming the stator, are thus accurately and rigidly located with respect to the rotor of the magneto.

The manner of operation of the magneto will be apparent from the above description and from the drawings, particularly Figs. 4 and 8. In Fig. 4 the rotor, which is assumed to be rotating clockwise, is in neutral position, that is, pole pieces of the rotor lie midway between the pole shoes of the stator. In such position the flux density in the pole pieces is substantially zero. When the rotor has turned 22½° from the neutral position of Fig. 4 into the full register position of Fig. 8, pole pieces of the rotor lie opposite the pole shoes of the stator, so that the flux density in the pole shoes is now at a maximum. It will be understood that the primary circuit of the coil 17 is opened by the breaker assembly 21 each time the rotor travels from a neutral to a full register position, and that the primary circuit is also opened each time the rotor travels from a full register to a neutral position. Since with the magneto shown there are four complete cycles of flux variations per revolution of the rotor, the primary circuit of the coil is opened and closed eight times during each revolution of the rotor. The magneto thus supplies the ignition needs of an eight cylinder, four cycle internal combustion engine when the rotor of the magneto is rotated in synchronism with the engine at one-half the crankshaft speed.

It will also be evident from the Figs. 4 and 8 that the two pole shoes 34, 35 and 34', 35' of the two respective opposed pole members 37 and 37' are connected in parallel, so that the flux in each of combined legs 15 is essentially the sum of the flux in the two pole shoes of each pole member. The two pole members are alternately confronted by opposed pairs of pole pieces on the rotor so that the flux through core 16 of the coil 17 alternates in polarity, thereby inducing voltage in the coil.

The electric current generating apparatus of the invention is of advantage because of its compactness and its efficiency of operation. The illustrative magneto has a generally rounded configuration, it being necessary merely to provide relatively low side and bottom bulges in the housing 10 to accommodate the pole member assembly 36, as shown in Fig. 4. Because each of the opposed pole members cooperates simultaneously with a plurality of pole pieces, the magnetic efficiency of the apparatus is high. The compact rigid pole member assembly may be readily and accurately made, and it may be easily incorporated in the stator in an accurately located position. The novel configuration of the pole shoes, wherein an extension is disposed substantially normal to the pole shoe and extends along but offset from the axis of the rotor, makes possible the positioning of the coil so as at least partially to overlie an end of the rotor. Consequently, the overall girth of the apparatus is decreased

while retaining high efficiency of the apparatus and ready accessibility of the coil.

Although only one embodiment of the invention is illustrated in the drawings and described in the foregoing specification, it is to be expressly understood that the invention is not limited thereto. For example, in some instances, particularly with a small number of pole pieces on the rotor, only one set of opposed pole shoes 34 and 34', or 35 and 35' may be employed. Also, the opposed pole members need not be connected as a unit prior to their incorporation in the housing, since the housing itself adequately locates and secures the pole members. Various changes may also be made in the design and arrangement of the parts illustrated as well as in the materials herein suggested as suitable without departing from the spirit and scope of the invention as it will now be understood by those skilled in the art.

What is claimed is:

1. A magneto comprising a rotor carrying a plurality of spaced magnetic pole pieces, a stator having two opposed sets of pole members cooperating with said rotor, the two sets of pole members being generally mirror images of each other, each set of pole members having one pole shoe located on one side of the axis of the rotor and another pole shoe located on the other side of the axis of the rotor, the pole shoes of both sets of pole members lying generally in the same plane transverse to the axis of the rotor, means magnetically connecting the pole shoes of each set together including an extension on each pole shoe having a leg extending parallel to the axis of the rotor, a coil, and a core for the coil having one end thereof magnetically connected to the legs of the extensions of one set of pole members and the other end thereof magnetically connected to the legs of the extensions of the other set of pole members, the sets of pole members being offset toward each other around the axis of the rotor, and the outer ends of the legs being offset toward each other around the axis of the rotor in the same direction as the offset of the sets of pole members.

2. A magneto as defined in claim 1 wherein the legs leading from the pole shoes of each set of pole members lie superimposed, closely adjacent, and parallel to each other.

3. Apparatus of the class described, comprising a housing, a rotor journalled within the housing and carrying

a plurality of spaced magnetic pole pieces, a stator in the housing having two opposed pole members each having a pole shoe cooperating with the pole pieces, each pole member including an extension connected to the pole shoe and including a leg, the legs of both pole members extending in the same direction generally parallel to the axis of the rotor, the outer ends of the legs lying outwardly beyond one end of the body of the rotor and being offset laterally to one side of the axis of the rotor, a coil partially axially overlying the body of the rotor, a removable core for the coil extending between and magnetically connecting the legs of the extensions, and a removable end plate on one end of the housing overlying the rotor and the core, the end plate carrying a bearing journalling the rotor, the coil and the rotor being removable from the housing axially thereof in the direction toward said one end of the housing upon removal of the end plate from the housing.

4. Apparatus as defined in claim 3, comprising thrust means interacting between the core and the end plate to retain the core against the ends of the legs when the end plate is in operative position.

5. Apparatus as defined in claim 3, wherein said one end of the housing is the rear end thereof, the rotor has a rotor shaft, the rotor shaft has a driving portion extending forwardly from the rotor, the legs of the pole members extend rearwardly, the outer ends of the legs lie outwardly beyond the rear end of the body of the rotor, and the coil is laterally offset from and partially axially overlies the body of the rotor at the rear end thereof.

6. Apparatus as defined in claim 3, wherein the pole shoes lie in the same plane transversely of the axis of the rotor and are offset angularly around the axis of the rotor in the same direction as the direction of offset of the outer ends of the legs of the extensions.
